UNITED STATES PATENT OFFICE.

WILLIAM R. FOX, OF GRAND RAPIDS, MICHIGAN, ASSIGNOR TO THE FOX MACHINE COMPANY, OF SAME PLACE.

RIVETING-MACHINE.

SPECIFICATION forming part of Letters Patent No. 557,986, dated April 7, 1896.

Application filed February 20, 1895. Serial No. 539,064. (No model.)

To all whom it may concern:

Be it known that I, WILLIAM R. FOX, a citizen of the United States, residing at Grand Rapids, in the county of Kent and State of Michigan, have invented certain new and useful Improvements in Riveting-Machines, of which the following is a specification, reference being had therein to the accompanying drawings.

10 My invention relates to the manufacture of sash-pulleys of sheet metal, and is designed specially to provide a simple and effective device to rivet the parts of the pulley or wheel together by the use of a tube of sheet metal commonly known as a "quill." In the manufacture of these pulleys I make them in sections out of sheet metal and secure the centers of the sections together by means of a short metal tube having its ends beaded over upon 15 the sections, serving not only to draw the sections together and hold them securely, but also to furnish a hub for the wheel, and by the apparatus made the subject of the present application I am enabled quickly and 20 perfectly to apply the quills to the wheel-sections and rivet them in place securely.

In the drawings, Figure 1 is a sectional view of a part of a press embodying my improvements. Fig. 2 is a front view of the collars and base. Figs. 3 and 4 are detailed sectional views.

In the figures the base of the press is shown at A, and secured to it is a circular disk B. The press-frame is seen at 7 and the plunger or slide at R. Secured within a socket in the disk and base is a hollow base-piece D, containing a strong compression coil-spring a. This piece D has an extension b, forming a mandrel or die carrier, and a collar C encircles the mandrel, resting upon an enlargement c of the mandrel when the parts are compressed. The collar C and the mandrel b are mortised, as shown in Fig. 2, and in this mortise is fitted a block E, held by the headed 45 screws 1 2, passing through the slots of the collar. Beneath this block E is a plug G, fitting the opening in the end of the base-piece D, and under the tension of the spring below it tending to press the block E upward. In 50 the upper end of the mandrel extension b is formed a socket, in which is secured a steel mandrel H, having a projecting center regis-

tering with the opening through the tube, while at the base of the center a groove is formed which has the effect under pressure 55 of turning outwardly the end of the tube into a bead over the edge of the opening in the wheel-section. It will be seen that the mandrel b and the collar C have their upper surfaces conforming to the configuration of one 60 of the pulley-sections, and the parts just described, being duplicated by like parts connected to the slide of the press, form, when together, the complete configuration of the pulley-shell. The parts of the shell are supported upon the lower collar C when the upper plunger, in the position of Fig. 3, begins to descend. In this position the springs in the base-pieces D D' have forced out the collars through the plugs G G' and blocks E E', and 70 the collars are thus in advance of the dies or mandrels. The pulley-sections are clamped between the faces of the collars C C' and properly centered, and then the further descent of the press-plunger begins to compress 75 and force back the collars against the pressure of the springs, which bring together the mandrels or dies with the effect of bending over the ends of the tube or quill, drawing the sections of the pulley together and firmly 80 securing them in place.

What I claim is—

1. In combination, a pair of spring-pressed collars, dies encircled by said collars, the adjacent faces of the said collars and dies being 85 shaped to receive the two parts of a pulley, a projecting center on each die registering with the center of the pulley-sections and fitted to receive a quill or tube and a central depression around each center, substantially as described. 90

2. In combination with the collars C C' the blocks E E', secured thereto, the plugs G G', the spring in rear of said plugs, the die-carriers and the dies, said dies having projecting 95 centers and the carriers and collars having adjacent faces conforming to the shape of the pulley-sections, substantially as described.

In testimony whereof I affix my signature in presence of two witnesses.

WILLIAM R. FOX.
